UNITED STATES PATENT OFFICE

MITCHELL L. FYKSE, OF SOUTH MILWAUKEE, WISCONSIN, ASSIGNOR TO BUCYRUS-
ERIE COMPANY, OF SOUTH MILWAUKEE, WISCONSIN, A CORPORATION OF DELA-
WARE

CREEPING TRACTION UNIT

Application filed September 7, 1926. Serial No. 134,001.

This invention provides an improved form of the endless tread-belt links illustrated in U. S. Patent No. 1,574,042, to Bager and Lehman, February 23, 1926.

5 Its principal object is to provide novel means for the extrusion of dirt from the wheel-engaging surface of the tread-links, for strengthening the links, and for securing the pins which fasten the links together. 10 These advantages will be explained more at length hereinafter, as the description progresses.

Other objects and advantages will be readily evident to anyone skilled in the art, and 15 therefore need not be herein more specifically set forth.

The invention consists in the novel parts and in the combinations and arrangements defined in the appended claims, and of which 20 one embodiment is exemplified in the accompanying drawings, which are hereinafter particularly described and explained.

As no changes in tumblers or rollers are contemplated in the present application, they 25 are not shown in the drawings.

Throughout, the same reference number is applied to the same or to similar members; and, for ease in comparison with the device of the said U. S. Patent No. 1,574,042, the 30 same reference numbers have been retained for corresponding parts, non-corresponding parts being herein numbered from 40 up. The sections, in all cases, are as viewed in the direction of the arrows.

35 Figure 1 is a plan of the link, as seen from above.

Figure 2 is a section, taken along the line 2-2 in Figure 1.

40 Figure 3 is a view, half in section and half in side view, the former as indicated by the line 3-3 in Figure 1.

Figure 4 is a section, taken along the line 4-4 in Figure 1.

45 Figure 5 is a view of the link, half in end

view and half in section, the latter as indicated by the line 5-5 in Figure 1.

Figure 6 is a view of one of the pivot pins which join successive links together.

Figure 7 is a plan view of the retaining 50 pin which holds in place the pin shown in Figure 6.

Figure 8 is an end view of the retaining pin shown in Figure 7.

55 My improved creeping traction tread consists of similar links, one link being shown and indicated generally by the numeral 23. This link is preferably made hollow in order to reduce its weight, and with an outer wall 24, constituting the tread, or ground-engaging portion, and a skeleton inner wall, 25. These walls are spaced apart by stiffening ribs or webs 24', which project inwardly from the outer wall 24 and merge into the skeleton inner wall 25.

65 The skeleton inner wall 25 carries, lengthwise of the link, a pair of centrally disposed parallel upstanding flanges 26, spaced apart a distance corresponding to the width of the rims of the rollers and tumblers. The flanges 70 26, extending longitudinally of the several links of the tread belt, together define a centrally disposed wheel-receiving guideway or channel along the inner face of the tread belt. The flanges 26 have upwardly a slight 75 flare outward from the channel, to ensure freedom of entrance into and exit from engagement of the wheels with the channel.

Each link extends somewhat beyond the ends of the channel formed by the flanges 26, so 80 as to provide a space between the ends of the channels of adjacent links for the reception of the lugs of the driving tumblers. A positive drive connection is thus established 85 between the driving tumblers and the tread belts.

That portion of the inner wall 25 of my link which constitutes the base of the guideway is substantially flat so as to provide a fairly smooth track for the rollers.

For the purpose of hingedly connecting adjacent links, each link is provided at one edge with a pair of pivot ears 27, spaced apart a distance substantially greater than that which separates the flanges 26. That portion of the edge which is between said ears is substantially straight, for purposes of strength and rigidity, and to permit a close fit with the adjoining edge of the adjacent link, thereby preventing the intrusion of earthy material between the links. The opposite edge of the link is also substantially straight, except for appropriate recesses formed therein to receive snugly the pivot ears 27 of the adjacent link. Pivot pins 28 are passed through the inter-engaging parts thus formed.

In the features discussed above, my link is substantially the same as that shown in the said patent to Bager and Lehman. In the said patent, the pivot pin 28 is retained in its operative position by a retaining pin (shown in said patent as number 29), which passes through a hole drilled in said pivot pin and through a cooperating hole in an adjacent web of the link. This construction restrains the pivot pin from rotating with respect to one of the two links it connects, namely: that one which contains the adjacent web just mentioned.

It will be noticed that my link differs from the previous link principally in the following three items:

(1) I have entirely eliminated all the difficulties caused by the restraint from rotation, formerly imposed upon the pivot-pin by the retaining pin. My pivot-pin 28 is not weakened by a hole drilled through it. My pivot-pin is in no way restrained from rotation with respect to either of the links it connects; so that, if it becomes bound with respect to either one of the links, it may rotate freely with respect to the other. When my pivot-pin is in position, its end inward of the link abuts against a web 49 and a retaining pin 40 is inserted into a cylindrical hole in the adjacent web 41, which web, it will be seen from the drawings, is thick enough to furnish a sufficient bearing surface to hold the retaining pin 40 securely. The retaining pin has its head 42 made with a rectangular cross section, so that a large flat surface is presented for abutment against the outer end of the pivot-pin 28, to retain the latter in place. That end of the retaining pin which has been inserted into the cylindrical hole in the web 41 is provided with a drill hole 43, for the reception of a split pin (not shown), whose purpose is to hold the retaining pin in its place.

(2) My link further differs from the former link in that each flange 26 is provided with a hole 44 to permit the wheels to extrude dirt from the wheel-engaging channel 45, these flanges 26 being provided with a reinforcement 46, to compensate for the weak-

ening that would otherwise be caused by the presence of the hole 44.

(3) The third important improvement in my link over previous links is the use of the double web 47, 48, which carries the stress caused by the tension of the tread belt very directly from each ear 27 to the recess in which the corresponding ear of the next link fits, and thus eliminates unnecessary strain in those portions of the link which are out of the direct line from said ear to said recess.

It must be evident to anyone skilled in the art to which my invention pertains that I provide a link which is both novel and useful; which is simple and relatively cheap and easy to construct because of the skeleton inner wall; which, though relatively light for the same reason, is stronger than former links because of a better disposal of the stiffening webs; and which will not become clogged with dirt. Also, that I have provided a means of hingedly connecting such links into a belt, which means is simpler, stronger and more lasting than those used in former belts, thus ensuring less annoyance and waste of time and money in making repairs and replacements necessitated by breakages.

While I have shown and described but one form of my improved creeping traction tread, I wish it to be understood that I do not purpose to be limited to the particular construction shown, but rather that I reserve to myself the right to make any modifications or changes that are within the scope of the appended claims.

I claim:

1. A tread belt link for creeping traction mechanisms having: a broad ground-engaging surface on one side thereof; a narrow wheel-receiving channel, centrally disposed, on the other side thereof; and upstanding wheel-guiding flanges, containing openings for the extrusion of dirt from the wheel-receiving channel by the action of the wheels.

2. A tread belt link for creeping traction mechanisms having: a broad ground-engaging surface on one side thereof: a narrow wheel-receiving channel, centrally disposed, on the other side thereof; and upstanding wheel-guiding flanges, containing openings for the extrusion of dirt from the wheel-receiving channel by the action of the wheels, said flanges being each thickened along its upper edge, to compensate for said openings.

3. A tread-belt for creeping traction mechanisms, having: a broad ground-engaging surface on one side thereof; a narrow wheel-receiving channel, centrally disposed, on the other side thereof; and two rows of upstanding wheel-guiding flanges, containing openings for the extrusion of dirt from the wheel-receiving channel by the action of the wheels.

4. A tread belt for a creeping traction mechanism, comprising: a series of connected links, having a broad ground-engaging sur-

face on one side thereof, a single narrow wheel-receiving channel, centrally disposed, on the other side thereof, and a row of up-standing wheel-guiding flanges, disposed on each side of said channel, portions of each row being cut away to provide openings for the extrusion of dirt from said channel by the action of the wheels.

5 In testimony whereof I affix my signature.
